UNITED STATES PATENT OFFICE.

CHARLES H. CHILDS, OF CLEVELAND, OHIO.

VAPOR-BURNER.

SPECIFICATION forming part of Letters Patent No. 399,183, dated March 5, 1889.

Application filed October 24, 1887. Serial No. 253,265. (No model.)

To all whom it may concern:

Be it known that I, CHARLES H. CHILDS, of Cleveland, in the county of Cuyahoga and State of Ohio, have invented certain new and useful Improvements in Vapor-Burners; and I do hereby declare the following to be a full, clear, and exact description of the invention, such as will enable others skilled in the art to which it pertains to make and use the same.

10 My invention relates to improvements in vapor-burners in which the burner-cap for heating has a serrated lower edge and sits on a flange of the commingling-chamber, the latter having a series of radial grooves made to mismatch the serrations of the cap, to the end that the jets of flame issuing from the burner are thus made irregular in cross-section and thereby present greater surface to the action of the air, and better results accrue in consequence of such irregular flame-jets.

15 My invention also relates to the details of construction hereinafter described, and pointed out in the claims.

In the accompanying drawings, Figure 1 is an elevation in section. Fig. 2 is a bottom plan. Fig. 3 is a top plan view of the primary commingling-chamber, and Fig. 4 is an elevation with parts in section.

20 A represents the stand-pipe, that screws into a boss, b', the latter being integral with the primary commingling-chamber B. This commingling-chamber has the ordinary cup-shaped formation and is provided with depending eduction-tubes C and D. Ribs c and d on the under surface connect the said tubes with the boss b', with retorts c' and d' formed in the ribs to connect internally the upper end of the stand-pipe to the respective eduction-tubes C and D. The primary commingling-chamber has a laterally-projecting boss, 25 E, cored to form the secondary commingling-chamber E', from which leads the tube F, which connects with the lighting-burner. (Not shown.) The chamber B has cup-shaped depressions B', and in a central hole made through the bottom wall of such depression is placed an induction-tube, H, the latter being provided with a drip-hole, h, for supplying the lighting-cup G. Primary commingling-chamber B terminates in a broad laterally-projecting flange, B², the upper surface

of the flange forming a seat for the burner-cap I. This cap has a depending rim, the lower edge of which is serrated, as shown at i, while the flange B² has a series of radial 55 grooves, b, that mismatch with the serrations of the cap by reason of there being a greater number of the one than of the other. Depending wings I' of the cap hold the latter in a central position on the flange B². Valve-arm C' screws into the lower end of eduction-tube C, such valve-arm having a duct, c², that leads to the jet-orifice c³, the latter being regulated by a needle-valve, c⁴, while the duct is closed by a hand-valve, C². Valve-arm D' 60 screws into the lower end of eduction-tube D, this arm having a duct, d², leading to the jet-orifice d³, the latter being regulated by a needle-valve, d⁴, with hand-valve D², for closing the duct. Jet-orifice c³ discharges into 65 the induction-tube H for supplying the primary or heating burner, and jet-orifice d³ discharges into an induction-tube, e, for supplying a lighting-burner. The tube e screws into a threaded hole in the bottom wall of boss E, 70 75 by means of which the tube can be raised or lowered to bring the bottom end thereof in such juxtaposition with jet-orifice d³ as will regulate the supply of air to give the best results at the lighting-burner. An internal upwardly-projecting flange, e', prevents any drip through induction-tube e in case of condensed vapor returning to the secondary commingling-chamber E'.

80 The orifice where tube F is inserted is usually of considerable size for convenience in coring chamber E', a bushing, e², being employed to reduce the orifice to the size of the pipe F, thus leaving considerable space below the pipe at the bottom of chamber E' for receiving condensed vapors. Boss E, being integral with the primary generator, is kept intensely heated by the heating-burner, and any liquid in chamber E' had from condensation of vapors in pipe F is quickly revaporized. 85 90

95 The tube F leads first laterally and then upward to bring the lighting-burner to the desired location, usually some feet above the top of the stove and so far to one side as to be entirely out of the way. As aforesaid, the 100 needle-valves c⁴ and d⁴ are set to regulate the discharge of the respective jet-orifices, and

may be changed a trifle from time to time if necessary by the aid of a wrench. These jet-orifices, therefore, are not enlarged or injured by closing of these valves, and the operator in starting the stove has no nice adjustment of valve to make, but, on the contrary, can turn valves C² and D² wide open.

Through inadvertence frequently valve C² is closed to extinguish the heating-burner, leaving valve D² wide open, in consequence of which there is a waste of gasoline as soon as the generator cools down. To avoid this I mount disks C³ and D³ on the respective valve-stems, these disks being made to overlap each other and abut each other when the valves are open or closed, disk C³ being placed outside, as shown in Figs. 1 and 2. With this arrangement valve D² must be closed before it is possible to close valve C². By reason of grooves b and serrations i, arranged as aforesaid, the jets of flame issuing from the heating-burner, instead of being round, are thin and irregular in cross-section, thus exposing a great surface of flame to the air, and this is found to add considerable to the heating capacity of the burner.

The heating-burner is operated substantially the same as ordinary burners. The gasoline, being first admitted through jet-orifice c³, strikes burner-cap I, and, falling back into the cup B', is discharged from thence through the orifice h and induction-tube H into the lighting-cup below. After the heating-burner is in full operation, by means of valve D² vapor may be discharged to the lighting-burner whenever it is needed.

What I claim is—

1. The combination, with the commingling-chamber having a laterally-projecting flange and a series of radial grooves in the top surface of the flange, of a burner-cap having a series of notches or serrations in its underside, said burner-cap being adapted to rest on the flange of the said commingling-chamber, substantially as set forth. 40

2. The combination, with a commingling-chamber having a laterally-projecting flange with a series of grooves on the surface of the flange, substantially as indicated, of a burner-cap having a depending rim with a serrated lower edge, said serrations being made to mismatch the grooves of the generator-flange, and wings connected with the burner-cap for engaging the inner wall of the primary commingling-chamber to hold the cap centrally, 50 substantially as set forth.

3. The combination, with primary and secondary induction-tubes, of valve-arms having ducts and jet-orifices, hand-valves for opening and closing the ducts, and stops mounted on the respective valve-stems, said stops overlapping and abutting each other, with the valves in open or closed position, substantially as set forth. 60

In testimony whereof I sign this specification, in the presence of two witnesses, this 30th day of August, 1887. 65

CHARLES H. CHILDS.
